US00D764175S

(12) **United States Design Patent**
Jimenez et al.

(10) **Patent No.:** US D764,175 S
(45) **Date of Patent:** ** Aug. 23, 2016

(54) **TOOTHBRUSH**

(71) Applicant: **COLGATE-PALMOLIVE COMPANY**, New York, NY (US)

(72) Inventors: **Eduardo Jimenez**, Manalapan, NJ (US);
Robert Moskovich, East Brunswick, NJ (US); **Andreas Wechsler**, Zell am See (AT); **Achim Storz**, Zel am See (AT)

(73) Assignee: **COLGATE-PALMOLIVE COMPANY**, New York, NY (US)

(**) Term: **14 Years**

(21) Appl. No.: **29/476,688**

(22) Filed: **Dec. 16, 2013**

(51) LOC (10) Cl. **04-02**

(52) U.S. Cl.

USPC **D4/104**

(58) **Field of Classification Search**

Primary Examiner — Keli L Hill

CLAIM

The ornamental design for a toothbrush, as shown and described.

DESCRIPTION

FIG. 1 is a front perspective view of a toothbrush according to the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a greatly enlarged top view thereof;

FIG. 8 is a greatly enlarged bottom view thereof;

FIG. 9 is an enlarged detail view of area 9 of FIG. 1;

FIG. 10 is an enlarged detail view of area 10 of FIG. 3; and, FIG. 11 is an enlarged detail view of area 11 of FIG. 2.

The portions of the handle shown in broken lines form no part of the claimed design.

1 Claim, 6 Drawing Sheets
